UNITED STATES PATENT OFFICE.

ARTHUR WILLIAM CLAYDEN, OF EXETER, ENGLAND.

GAS, GASOLENE, OR INFLAMMABLE-VAPOR ENGINE.

SPECIFICATION forming part of Letters Patent No. 694,090, dated February 25, 1902.

Application filed July 26, 1901. Serial No. 69,836. (No model.)

To all whom it may concern:

Be it known that I, ARTHUR WILLIAM CLAYDEN, a subject of the King of Great Britain, residing at St. John's, Polsloe road, Exeter, 5 England, have invented new and useful Improvements in Gas, Gasolene, or Inflammable-Vapor Engines, of which the following is a specification.

This invention relates to improvements in 10 gas, gasoline, and inflammable-vapor engines.

According to the invention I make use of a device which I term a "charging-valve" for receiving the explosive charge, previously compressed by pumps or other suitable means, 15 and for delivering the said charge into the combustion-chamber of the engine, as hereinafter described.

In carrying out the invention the charging-valve comprises a chamber which can rotate 20 in a suitable casing and is so constructed that at the required moment it opens into the main combustion-chamber of the motor and the charge is fired. Communication is then 25 closed between the movable chamber and the explosion-chamber and the charging-valve is opened to an exhaust-port. Before the latter is shut off the valve is put into communication with an air-inlet, so that air is admitted to sweep out the products of combustion 30 which still remain in the valve. The ports for admitting the explosive charge are then opened and the cycle of operation recommences.

In practice I advantageously construct the 35 charging-valve of a hollow conical plug which rotates in a conical casing preferably provided with a water-jacket for cooling purposes, the said conical valve having an opening which when the valve is rotated is successively 40 brought opposite the ports which communicate with the explosive-charge supply, the combustion-chamber of the motor, and the valve-exhaust.

To enable the invention to be fully understood, I will describe it by reference to the accompanying drawings, in which—

Figure 1 is a longitudinal section of a form of charging-valve constructed according to the invention. Fig. 2 is a transverse section thereof; and Figs. 3, 4, and 5 are views similar to Fig. 2, but showing the valve in different

positions. Fig. 6 is a side elevation of a motor having my improvements applied thereto. Fig. 7 is a plan view thereof, and Fig. 8 is a horizontal section of the valve and 55 cylinder end. Fig. 9 is a top plan view of a motor embodying a slight modification of my invention.

a is the casing, which is provided with the cooling-jacket *b* and with a base or flange *a'*, 60 by means of which it can be bolted to the main combustion-chamber of the motor.

c is the valve, which is hollow and is conical in shape and which fits into the similarly-shaped recess in the casing *a*, as clearly shown 65 in Fig. 1. This valve *c* is provided with a lateral opening *c'* and at the top and bottom with spindles *d* and *e*, respectively, which are held in bearings in the casing *a*, the lower spindle *e* being advantageously supported by 70 the adjusting device *f*, by means of which the pressure between the coned surfaces of the valve and casing may be adjusted.

g is the opening in the casing *a* into the combustion-chamber *g'* of the motor. *h* is 75 the exhaust-port provided in the said casing for the products of combustion from the valve *c*.

i is the port in the casing through which compressed air is allowed to enter the valve 80 *c* to sweep out the products of combustion which do not pass out through the exhaust-port *h*, and *j* and *k* are the inlet-ports for the compressed air and inflammable gas, respectively, which form the explosive charge 85 introduced into the valve *c*. Instead of providing separate ports for the introduction of the gas and air the charge can be mixed outside the valve, into which it can pass through a single port.

The valve *c* can be rotated in the casing *a* by any desired means—for example, by a suitable connection with the main driving-shaft of the motor, as shown in Figs. 6 and 7. In this arrangement the projecting spindle *d* of 95 the plug *e* has keyed upon it a bevel-wheel *l*, gearing with a bevel-pinion *l'* upon one end of a spindle *m*, rotatably held in bearings *m'* on the engine, the other end of the said spindle carrying a bevel-pinion *n*, gearing 100 with a bevel-wheel *n'* upon the crank-shaft *o*. With this mechanism as the crank-shaft ro-

tates it revolves the bevel-wheel l , and consequently the valve c . The rotation of the valve also produces the igniting-spark by the contact-arm l^2 , which once each revolution makes contact with the spring-arm l^3 .

5 In the drawings I have shown an electric ignition device for the explosive charge, the said device comprising a plug l^0 , which is passed down through the spindle d of the valve c .

The operation of my charging-valve is as follows: Assume the valve to be in the position indicated in Fig. 2—that is to say, such that communication is open for the charge of 15 compressed air and inflammable vapor to enter through the ports jk . The rotation of the valve c in the casing a then gradually brings the opening c' in the valve opposite the opening g in the casing a , as shown in Fig. 3, so 20 that the explosive charge contained in the valve expands into the combustion-chamber of the motor. The charge is then exploded, and the valve c , continuing its motion, the opening c' is brought opposite the exhaust-port h in the casing a , as shown in Fig. 4. The products of combustion then partially 25 escape through the said port, and the further movement of the valve brings the opening c' into communication with the compressed-air port i while it is still in communication with the exhaust-port h , as shown in Fig. 5. A jet of air thus rushes into the valve c , and the remainder of the products of combustion is 30 swept out through the said port h . The further rotation of the valve brings the port c' again into communication with the inlet-ports jk , so that it receives a fresh explosive charge 35 and the cycle of operation begins *de novo*.

The main combustion-chamber g' of the engine provided with my device is furnished 40 with a separate exhaust p , which is held open by any ordinary means (such as the cam q on the spindle q' , actuated from the crank-shaft by the bevel-gear g^2) during the whole of the 45 instroke of the piston and is closed just before the charge is fired. The stroke of the piston is arranged such that the products of combustion are almost completely swept out of the cylinder, only a small clearance-space 50 being retained.

In practice the dimensions of the valve depend upon, first, the degree of expansion desired; second, the initial pressure of the charge, and, third, the dimensions of the main 55 combustion-chamber. The following formula can be used for obtaining the dimensions:

$$\text{Log. } r = \frac{\text{Log. } R^2 1 - \text{log. } 2 N}{3}$$

60 Where r equals the mean inside radius of the valve-chamber a , $2r$ representing the inside length thereof. R equals the radius of the main combustion-chamber. 1 equals the length of the stroke of the piston. N equals 65 the ratio of the expansion required to the volume of the compressed charge. For small or roughly-constructed engines N should not be

larger than three or four; but in larger engines of good quality it may rise to six, seven, or more.

70 In practice for single-acting engines the charging-valve should advantageously be fixed by its casing to the end of the cylinder and the rotation of the valve arranged so as to give an explosion at each outstroke of the 75 piston—that is to say, at each revolution of the driving-shaft. Furthermore, by providing one end of the cylinder with two valves and furnishing means whereby one of each pair of valves can be closed at will the motor 80 can be run at half-power without lessening the advantages derived from the employment of full compression. Such a construction is illustrated in Fig. 9 of the drawings, in which the cylinder is shown provided with two of 85 the valve-casings $a^2 a^2$, in each of which is arranged one of my combined rotary combustion chamber and valve having its spindle provided with a bevel-wheel l^2 , meshing with a bevel-pinion l^3 on a spindle m^2 , mounted in 90 bearings on the machine. Each of said spindles m^2 carries a bevel-pinion n^2 at its other end gearing with a bevel-wheel n^3 on the crank-shaft of the engine, one of said bevel-wheels n^3 being located at each side of the 95 engine. Each of the pinions l^3 is loosely mounted on its spindle m^2 —as, for instance, by being secured to a sleeve l^4 , revolvably mounted on the spindle m^2 and adapted to be secured thereto by a clutch l^5 , operated by a 100 hand-lever l^6 . The other parts shown in Fig. 9 are identical with those previously described. By throwing either of the clutches l^5 out of 105 operative engagement the corresponding combustion-chamber will be stopped from rotating, and the engine can then be operated with half the charge.

The word "gas" or "vapor" referred to in the preceding description is to be understood to include any gas, vapor, or mixture of gases 110 and vapors which is capable of producing an explosive mixture with a suitable proportion of air.

Having now particularly described and ascertained the nature of my said invention and 115 in what manner the same is to be performed, I declare that what I claim is—

1. In an explosive-engine, the combination with the cylinder and piston, of a single explosion-chamber, separate from and normally 120 out of communication with said cylinder and capable of containing the entire explosive charge, means for supplying the explosive charges to said chamber, an igniting device, means for temporarily establishing communication between said cylinder and said chamber without altering the position of said chamber with respect to the cylinder, an exhaust-port for said cylinder, and a separate exhaust-port for said chamber, substantially as described.

2. In an explosive-engine, the combination with the cylinder and piston, of a single explosion-chamber, separate from and normally

out of communication with said cylinder and capable of containing the entire explosive charge, means for supplying the explosive charge to said chamber, an igniting device, 5 means for temporarily establishing communication between said cylinder and said chamber without altering the position of said chamber, with respect to said cylinder, an exhaust port for said cylinder, a separate exhaust port for said chamber, and means for introducing air under pressure into said chamber to force out the products of combustion, substantially as described.

3. In an explosive-engine, the combination 15 with the cylinder, provided with an inlet-port and a piston, of a revoluble explosion-chamber separate from said cylinder constructed to rotate upon its own axis, capable of containing the entire explosive charge, and provided with a port adapted to register with the inlet-port of said cylinder, means for supplying explosive charges to said chamber, an exhaust for said chamber, a separate exhaust for said cylinder, and means for rotating said 25 chamber, substantially as described.

4. In an explosive-engine, the combination with the cylinder, provided with an inlet-port and a piston, of a revoluble explosion-chamber separate from said cylinder, capable of 30 containing the entire explosive charge, and provided with a port adapted to register with the inlet-port of said cylinder, means for supplying explosive charges to said chamber, an exhaust for said chamber, a separate exhaust 35 for said cylinder and connections between said chamber and the engine for rotating the chamber, substantially as described.

5. In an explosive-engine, the combination 40 with the cylinder provided with an inlet-port and an exhaust-port, of a single revoluble explosion-chamber constructed to rotate upon its own axis, provided with a port adapted to register with the inlet-port of said cylinder, a casing for said chamber, provided with an 45 exhaust-port, an inlet-port for compressed air, and an inlet-port for admitting explosive material, an igniting device, for the explosive charge, and means for rotating said explosion-chamber, substantially as described.

50 6. In an explosive-engine, the combination

with the cylinder provided with an inlet and exhaust port, and the piston, of a casing provided with a conical interior, a hollow revoluble conical chamber, mounted in said casing constructed to rotate upon its own axis 55 and provided with a port adapted to register with the inlet-port of the cylinder, means for supplying explosive charges to said chamber, an exhaust for said chamber, means for rotating said chamber, and devices for adjusting said chamber in said casing in a direction longitudinally of the axis of rotation of said chamber, substantially as described.

7. In an explosive-engine, the combination with the cylinder provided with an inlet and 60 exhaust port, and the piston, of a casing provided with a conical interior, a hollow revoluble conical chamber, mounted in said casing constructed to rotate upon its own axis and provided with a port adapted to register 65 with the inlet-port of the cylinder, said chamber being provided with axial spindles, mounted in said casing, said casing being provided with inlet-ports for the explosive charges and an exhaust-port, means for rotating said 70 chamber and an adjusting mechanism engaging one of said spindles, substantially as described.

8. In an explosive-engine, the combination with the cylinder provided with inlet and 80 exhaust ports and a piston in said cylinder, of a plurality of independently-revoluble explosion-chambers mounted adjacent to one end of said cylinder each constructed to rotate upon its own axis and provided each with a 85 port adapted to register with one of the inlet-ports of said cylinder, means for supplying an explosive charge to each of said chambers, a separate exhaust-port for each chamber independent of the cylinder exhaust-port, mechanism for revolving said chambers from the engine-shaft, and mechanism for throwing one or more of said chambers out of operation, to reduce the power of the engine, substantially as described.
